UNITED STATES PATENT OFFICE.

WILLIAM W. NEIGHBOUR, OF SPARTANBURG, SOUTH CAROLINA, ASSIGNOR OF ONE-HALF TO JOHN S. CROMER, OF SPARTANBURG, SOUTH CAROLINA.

ROCKER-ARM-SHAFT BEARING.

1,355,060.

Specification of Letters Patent.

Patented Oct. 5, 1920.

Application filed August 25, 1919. Serial No. 319,548.

To all whom it may concern:

Be it known that I, WILLIAM W. NEIGHBOUR, a citizen of the United States, residing at Spartanburg, in the county of Spartanburg and State of South Carolina, have invented new and useful Improvements in Rocker-Arm-Shaft Bearings, of which the following is a specification.

In loom operation the rocker arm shaft oscillates and there is therefore a tendency for said shaft to wear unevenly or at one side thereof, with the result that lost motion of the shaft is permitted in an up and down direction which is materially objectionable because it gives rise to breakage of the threads in the battery of the loom.

The object of my present sole invention is the provision of an advantageous bearing that will preclude uneven wear of the rocker arm shaft, notwithstanding the oscillatory character of the movements thereof.

The invention also contemplates the provision of a bearing having the capacity stated, and adapted to be adjusted in order to take up wear.

To the attainment of the foregoing, the invention consists in the improvement as hereinafter described and definitely claimed.

In the accompanying drawings, hereby made a part hereof:

Figure 1 is an elevation showing the bearing constituting the best practical embodiment of my invention of which I am cognizant, as properly arranged relative to a rocker arm shaft and the adjacent parts of a loom.

Fig. 2 is a vertical section of the same, with the shaft in elevation.

Fig. 3 is a section taken at right angles to Fig. 2, and in the plane indicated by the line 3-3 of said figure.

Fig. 4 is a section taken through the saddle block, and shaft in the plane indicated by the line 4-4 of Fig. 2.

Fig. 5 is a face view of the boss and the plate by which the same is carried.

Fig. 6 is an end elevation of the saddle block.

Similar numerals of reference designate corresponding parts in all of the views of the drawings.

The loom frame portion 7 and the plate 9 equipped with the boss 10 and connected at 8 to the frame portion, are of the ordinary well known construction, and the rocker

arm shaft 11 is disposed in the boss 10 in the usual manner.

In the carrying out of my invention a saddle block 12 is made to straddle the shaft 11. The said block is equipped with three screws 18, which are relatively arranged as shown, and are set against the shaft 11 so as to cause the saddle block to oscillate with the shaft. The said screws 18 are also for adjustment purposes to take up wear, and hence they may be properly denominated combined set and adjusting screws. At 13 the saddle block is provided with an annular flange that overhangs the boss and is spaced therefrom and is provided at 13^a with retainers. In the space afforded on the flange 13 and between the same and the opposed portion of the boss 10, I may employ anti-friction members 16 in the form of rollers or balls, or in lieu of said members I may occupy the space with the substance well known on the market as "bakelite delecto."

When my improvement is properly applied as illustrated, it will be observed that the weight of the shaft is transferred to the top of the bearing, and when wear takes place at the top of the bearing, such wear may be expeditiously and easily taken up by an attendant by simply screwing the upper screws 17 downwardly and loosening 85 to a corresponding extent the lower screws 18. It will also be observed that the arrangement of the flange 13 above and in spaced relation to the bearing is materially advantageous, inasmuch as any dust or dirt 90 that may find its way into the anti-friction means employed will tend to gravitate away from such anti-friction means, and hence will not in any degree impair the usefulness thereof.

In addition to the practical advantages hereinbefore ascribed to my novel bearing, it will be noted that the bearing is susceptible of application to installations such as at present in use without entailing any change whatever in such installations and without the necessity of employing skilled labor or tools other than an ordinary wrench for the setting of the screws 18. From this it follows that the improvement 100 may as readily be removed from a rocker arm shaft when occasion demands.

An important advantage that attends the adjustment of the saddle block relatively to the rocker arm shaft, lies in the fact that the 110

said adjustment obviates any canting of the saddle block away from the frame portion 7. This is due to the fact that the vertical plane of the upper screw 17 is more remote from the plane portion 7 than the vertical plane of the lower screws 18.

Having described my invention, what I claim and desire to secure by Letters-Patent, is:

- 10 1. The combination of a loom frame, a plate secured to said frame and having a boss, a rocker arm shaft journaled in said boss, a saddle block on the shaft beyond the boss and having an arch portion extending 15 to the frame and disposed above and spaced from the boss, anti-friction means between the boss and said arch portion, lower screws in the saddle block and engaging the lower

portion of the shaft at opposite sides of the vertical center thereof, and an upper screw 20 engaging the central portion of the shaft; the lower screws being nearer than the upper screw to the flange.

2. The combination of a loom frame, a plate secured to said frame and having a 25 boss, a rocker arm shaft journaled in said boss, a saddle block arranged on the shaft beyond the boss and fixed to the shaft and having an arch portion extending to the frame and disposed above and spaced from 30 the boss, and anti-friction means arranged between the boss and said arch portion and covered by the arrangement thereof relatively to the frame.

In testimony whereof I affix my signature. 35
WILLIAM W. NEIGHBOUR.
